UNITED STATES PATENT OFFICE.

NICOLAS EMILIEU MÉTHLIN, OF PARIS, FRANCE, ASSIGNOR TO SCHNEIDER & CIE., OF PARIS, FRANCE, A LIMITED JOINT-STOCK COMPANY OF FRANCE.

MEANS FOR IGNITING THE BURSTING CHARGE OF PROJECTILES.

Application filed July 20, 1926, Serial No. 123,675, and in France July 24, 1925.

The present invention relates to improvements in means for igniting the bursting charge of projectiles such as shells, explosive arrows or others. The invention consists essentially in a means combined with a percussion fuse and preventing the return of the flame when the firing is transmitted from the fuse to the charge; in other words the invention consists in a special arrangement of an additional member, combined with the fuse, or formed by one of the members of the fuse, this arrangement being such that the flame from the percussion cap of the fuse or the flame from a detonating percussion cap is wholly and in the most efficient manner possible transmitted to the explosive charge.

The invention is more particularly adapted to use in explosive arrows combined with a supersensitive fuse operating by driving in and inertia in which the parts of the firing mechanism (striker and percussion cap) are enclosed in a common container retained upon the fuse body or upon the projectile and becoming separated from the latter in order to make an inward movement as soon as the mechanism encounters an obstacle offering even only a very small amount of resistance.

According to the invention the flame from the percussion cap igniting the charge is prevented from being propagated outwards by a safety disc or gasket which is adapted to be deformed under the effect of the operation of the fuse and may, for example, be made of a metal of high molecular density such as lead, this disc being integral or virtually integral with the striker or associated with the latter in such a way as to form with it a closing member completely preventing any return towards the exterior of the flame or the gases from the igniting percussion cap.

Various examples of employment and construction of the invention are illustrated in the accompanying drawing, in which:

Figure 1 is a sectional elevation showing the invention applied to an explosive shell, the members being shown at rest.

Figure 2 is an elevation with part in section showing the arrangement formed by the conjugation of the striker and the deformed safety disc preventing, at the moment of ignition, any passage outwards of the gases and the flame from the detonating percussion cap.

Figure 3 is a view similar to the one shown in Fig. 2, illustrating a modification in which

the closing device is combined with a lodgment and a container or casing of special form for the detonating percussion cap.

Figure 4 is a partial sectional elevation of an explosive arrow constructed to receive a percussion fuse, which comprises the closing device according to the invention; the members in this figure are shown at rest.

Figure 5 is a detail view in plan of the safety disc constructed and formed in such a way as to form, with the striker, a closing device.

Figure 6 is a section similar to that shown in Fig. 4 the members being shown in the position they occupy at the moment the percussion cap is struck following an encounter with an obstacle.

Fig. 7 shows a plurality of arrows provided with a protecting cap for transportation.

Fig. 8 is a plan view of Fig. 7.

In the example shown in Figs. 1 and 2, A is a fuse body screwed into the nose of a shell B and said fuse body comprises at its lower part a lodgment a for the support C¹ carrying a detonating percussion cap C adapted to be ignited by the impact of a striker D guided in a duct a¹ formed in the said fuse body. In order to produce this ignition the striker is driven back towards the detonating percussion cap in the known manner, by the pressure of the gases produced by the operation of a percussion or time fuse of any known type. The drawing illustrates, simply by way of example, a super-sensitive fuse such as that disclosed in the patent to L. E. Remondy, No. 1,459,075, dated June 19, 1923, with a movable carriage F, operating by driving in and inertia, that is to say by the driving in of the carriage after a retaining pin f has been sheared through and the displacement of detonator f² relatively to the striker by its inertia.

The closing device comprises a deformable safety diaphragm or disc E which, in this example, is integral with the striker D. The deformable disc or gasket is combined with a duct a², preferably convergent, for example frusto conical, formed in the fuse body in front of the guiding duct a¹. The outer edge of the disc E rests upon the larger base of this duct or is held at this point by any other suitable means, the arrangement D—E being thus normally prevented from moving towards the detonating percussion cap. Any

forward displacement may be prevented, for example, by small projections α^3 , formed upon the fuse body, beneath which the disc is secured.

- 5 When upon striking an obstacle, the operation of the fuse causes the arrangement D—E to be driven in under the effect of the pressure of the gases from the percussion cap f^2 , the needle D strikes the detonating percussion cap 70 C passing through a plastic joint C^2 which may be provided if desired. The disc E in becoming deformed takes up the shape of the seating α^2 , the arrangement D—E thus preventing in a perfect manner any communication between the exploder detonator and the outside, the arrangement D—E being further pressed upon its seating by the pressure of the gases from the percussion cap f^2 , so that the effects of the flame and of the explosion of the detonating percussion cap C are used for igniting and exploding the charge of the projectile in the best manner possible.

Owing to the very light mass of the striker D and safety disc E, it is possible to make the 25 disc of material which will be readily deformed as above described and yet be sufficiently strong to prevent any deformation of the same due to set back on firing the projectile.

30 Figure 3 shows a detonating percussion cap of special form, combined with a lodgment of corresponding shape, formed for example directly in the fuse body A, as shown in the figure, which enables the effects of 35 the explosion of the percussion cap to be made use of in a still better manner. The lodgment is divergent towards the interior, that is to say that it has longitudinal walls sloping outwards from top to bottom; it may be in the form of a cone frustum or of a 40 paraboloid, for example, so as to form a surface for reflecting, parallel to the axis of the projectile, all the forces which are exerted at right angles to this axis.

45 The flared percussion cap may advantageously be retained in the fuse body, as shown in the figure, by a retaining socket H which is easily destroyed by the gases produced by the explosion of the percussion cap itself and which is secured to the said fuse body by being crimped in a groove α^4 upon the latter.

In the example shown in Figs. 4, 5 and 50 6 A is a fuse body forming the front metallic end of a tube B, into which it is fitted by screwing, as shown in Fig. 4, or simply by being slipped in and crimped, as shown in Fig. 6, filled with an explosive charge, the rear end of this tube being formed by a set of fins b which are fitted on or produced by 55 deforming the material of the tube.

In this example the deformable safety disc or gasket which, in combination with the striker, forms a closing member is formed by one of the members of a super-sensitive 65 fuse operating by the driving in of a mov-

able carriage containing the mechanism, and by the inertia of the percussion cap entering into action when the carriage, liberated from the projectile, is stopped by an obstacle.

The fuse comprises a movable carriage 70 comprising a casing F with which the striker D, which is placed in front of it, is integral formed. Upon the rear end of the casing, pierced by an orifice F¹, rests the independent 75 percussion cap C. A deformable disc E in the form of a spherical cup or the like, provided with a small central orifice e, the edge of which disc has a diameter equal to that of the container F and of the duct in which the latter may move, is secured by two wings 80 E¹ between a shoulder α^5 upon the fuse body and a ring G over which the outer edge of the said fuse body A is bent down. As explained in connection with the embodiment shown in Figs. 1 and 2, the safety disc can 85 be made strong enough to prevent shearing due to set back on firing the projectile.

The deformable disc in this case performs three functions:

1. By means of its locked wings E¹ against 90 which the casing or cover F presses, since the apex of the disc bears upon the percussion cap, the disc forms a stiffening member between the carriage and the fuse body until an obstacle is struck, thus replacing the pin f of 95 the fuse shown in Fig. 1.

2. Until the carriage is released the disc forms at the same time a deformable distance piece between the striker D and the 100 percussion cap C thus fulfilling the function of the arrangement f^3 — f^4 (of the spring f^3 and the disc f^4) in the fuse shown in Fig. 1.

3. When, as the result of an impact with an obstacle even offering a very small amount of resistance, the very light carriage is 105 stopped and the wings E¹ are sheared off, the carriage F then becoming independent of the arrow A—B—C. By its own inertia the percussion cap continues its movement at the velocity of the arrow so that the deformable disc E, the central aperture e of which is closed by the point of the striker D, is flattened between the percussion cap and the fuse body, thus forming a perfect wad or packing preventing any escape between the outer surface of the carriage F and the lodgment, as 110 shown in Fig. 6.

The free space between the movable carriage and the front edge or face of the arrow may be filled with a cork wad or plug 115 I, glued upon the walls of the ring and if desired covered with a sheet of tin foil or other suitable protecting material.

Arrows provided with the super-sensitive fuse according to Figs. 4, 5 and 6 may be 120 packed in bundles or packets for transport, for example as shown in sectional elevation and in plan, in Figs. 7 and 8, in a bucket or trough J of suitable thickness which arrangement prevents an untimely actuation of 125 130

the firing mechanism and protects the mechanism of the bundle of arrows from being struck by enemy shells.

Claims:

5. 1. In a fuse body having an opening and a primer and striker mechanism mounted in said opening, gasket means mounted in said opening comprising a soft, malleable, metal disc adapted to be deformed into fixed flame-tight engagement with the walls thereof on actuation of said striker to prevent escape of flame in one direction through said opening. 65
10. 2. In a fuse body having primer and striker mechanism therein, a gasket adapted to be pressed into fixed tight engagement with said body by the gas pressure generated by detonation of said primer. 70
15. 3. In a fuse body having an opening therein, fuse mechanism in said opening, and a disk member mounted in said opening, the latter having converging walls adjacent said member, said disk member being deformed into fixed flame-tight engagement with said converging walls by detonation of said primer. 75
20. 4. In a fuse having an opening therein, a plurality of primer and striker mechanisms therein, and a piston member of soft, malleable material associated with one of said mechanisms, said opening having converging walls adjacent said piston, said member being adapted on actuation of another of said mechanisms to actuate said first named mechanism and to be deformed into fixed engagement with said converging walls of said opening. 80
25. 5. In a fuse having an opening therein, a plurality of primer and striker mechanisms in said opening, a disc member of soft malleable material mounted in said opening, one of said strikers being connected with said member, the detonation of one of said mechanisms deforming said member into fixed engagement with a substantial length of the wall of said opening and thereby actuating said last named striker. 85
30. 6. In a device of the class described, a primer and striker mechanism actuated on impact with an obstacle, a disk member deformed into engagement with the wall of the fuse on detonation of said primer, means for preventing motion of said disk outwardly of the device and a second primer and striker mechanism actuated by deformation of said disk. 90
35. 7. In a fuse having an opening therein, a pair of primer and striker mechanisms in said opening, one of said mechanisms being actuated by impact with an obstacle, and a flexible disk member immovably secured in said opening between said mechanisms, the detonation of said mechanism deforming said disk into tight engagement with said wall, the striker of the other of said mechanisms being actuated by such deformation. 95
40. 8. In a device of the class described, a primer and striker mechanism actuated on impact with an obstacle, a disk member deformed into engagement with the wall of the fuse on detonation of said primer, and a second primer and striker mechanism actuated by deformation of said disk, said second primer being contained in a recess having inwardly diverging walls to direct the flame thereof to the bursting charge of the projectile. 100
45. 9. In a nose fuse for projectiles, a chambered fuse body open to atmosphere on one side thereof, primer and striker mechanism mounted to slide in said chambered body and driven into the latter on impact with an object to detonate the projectile, a metal disc of soft malleable material deformable into flame-tight engagement with the walls of said chambered body, and means preventing movement of said disc toward the open side of said fuse body. 105
50. 10. In a nose fuse for projectiles, a fuse body having a chamber therein open to atmosphere at the nose of the projectile, striker mechanism mounted to slide therein and driven into said chamber on impact with an object, a primer in said chamber to detonate the projectile on driving in said striker mechanism, and a deformable gasket positioned in said chamber between said striker mechanism and said primer and adapted on such impact to be forced into flame-tight engagement with the walls of said chamber to completely close the latter to the passage of gases outwardly of said chamber. 110
55. 11. In a nose fuse for projectiles, a fuse body having a chamber therein open to atmosphere at the nose of the projectile, striker mechanism in said open end, a detonating primer in said chamber, and a metal disc of soft malleable material in said chamber between said striker mechanism and primer, said disc being deformed on detonation of the projectile into fixed tight engagement with the walls of said chamber. 115
60. 12. In a fuse body having an opening and a primer and striker mechanism mounted in said opening, a gasket mounted in said opening adapted to be deformed into fixed engagement with the walls thereof on actuation of said striker to prevent escape of flame in one direction through said opening, and means in said opening preventing movement of said gasket in said direction. 120

In testimony whereof I have signed this specification.

NICOLAS EMILIEN METHLIN.
